UNITED STATES PATENT OFFICE.

ALEXANDER LECKEY, OF CAMDEN, NEW JERSEY.

CALENDAR.

1,266,499.

Specification of Letters Patent. Patented May 14, 1918.

Application filed September 1, 1916. Serial No. 118,105.

To all whom it may concern:

Be it known that I, ALEXANDER LECKEY, a citizen of the United States, residing at Camden, in the county of Camden and State of New Jersey, have invented new and useful Improvements in Calendars, of which the following is a specification.

This invention relates to improvements in calendars and has for an object to provide a calendar of novel construction which will be capable of being used pivotally, thereby prolonging the life of the same so that it may be utilized for a number of years, instead of being discarded at the expiration of a calendar year.

Another object of the invention resides in a perpetual calendar having peculiar features of construction whereby the same may be conveniently set to disclose a proper date.

In carrying out the invention use is made of a movable date sheet designed to be reciprocated so that the numbers or dates thereon, indicating the days contained in a month, will be brought into proper registration or alinement with permanent columns designating the names of the days of a week, other means being provided to obstruct from vision certain of the highest numbers found on the date sheet, so that months containing only thirty days will not be recorded as containing thirty one. Month and year indicating means are also provided in connection with the calendar.

A further object of the invention resides in a calendar of the above character which will require adjustment at the expiration of each month and said adjustment may be readily accomplished in a simple and convenient manner.

Other objects reside in a calendar having the above enumerated features, the same being plain or ornamental in appearance, in accordance with the cost of manufacturing the same, of varying proportions and designed to accurately perform its assigned functions throughout the life thereof.

The invention accordingly consists in the novel features of construction, combination of elements and arrangement of parts which will be exemplified in the construction herein described and the scope of the application of which will be indicated in the following claim.

In the accompanying drawing, wherein is

shown one of the various possible embodiments of the invention, 55

Figure 1 is a front elevation of a calendar constructed in accordance with the present invention,

Fig. 2 is a vertical sectional view taken 60 through the same,

Fig. 3 is a horizontal section taken along the line 3—3 of Fig. 1,

Fig. 4 is a transverse section taken along the lines 4—4 of Fig. 1, 65

Fig. 5 is a view of the date carrying sheet, and

Fig. 6 is a view of the date eliminating slide.

Similar characters of reference refer to 70 similar parts throughout the views of the drawings.

Referring more particularly to the details of the calendar, the same in its preferred form consists of a holder or frame 1 in the 75 form of a rectangular plate, the same may be constructed of any suitable material, of any desired proportion, and may be attractively finished to present an artistic appearance. The frame 1 has formed therein a 80 substantially rectangular opening 2 and is also provided with a backing 3, in order to provide a chamber 4 immediately in the rear of the opening 2.

Movably positioned in chamber 4 and 85 supported by the backing 3 is a sliding date sheet 5, the latter being provided with suitable date numerals 6, which are arranged in thirteen vertical columns *b* and in six horizontal columns *c*. The opening 2, in width, 90 is equal to the width of six of the vertical columns *b* and in height to that of the columns *c* of the date sheet 5. The frame 1, contiguous to the opening 2, is provided with suitable indicia 7, designating the days 95 of the week, which is adapted to aline or register with the numerals in the column *b*.

The sheet 5 is movable, with respect to the opening 2, in order to compensate for the fact that the first day of a new month is 100 likely to fall upon a different day from that of a preceding month; for instance, if the first day of one month occurs on a Thursday, the date numeral 1 of the date sheet is moved to a position in vertical alinement 105 with the Thursday column which correctly positions the balance of the numerals upon the sheet 5 in their proper positions, *i. e.*, so

that the date of each day of the month will be directly beneath the day upon which it will fall. If the first day of the month should be Sunday, the date sheet 5 would be moved until the numeral 1 thereof alines with the Sunday column, and so on, as will be readily understood. It will be apparent, upon reference to Fig. 5 of the drawings, that the date sheet 5 is substantially double in width to that of the opening 2, so that when the position of the numeral 1 thereon is moved from the Sunday column to the Saturday column, the sheet 5 will always be visible through the opening 2. The date numerals upon said sheet are so arranged that regardless of the day of the week the numeral 1 thereof is positioned under, the numerals of the following days will be positioned in proper relation with the days of the week upon which they will occur.

The lower left hand corner of the opening 2 is provided with a communicating recess 8, which is utilized to record the last days 25 of a month, when the first days of the same fall upon either Friday or Saturday. The date numerals which register with the recess 8 are located upon the lowermost column *c* of the date sheet 5.

30 In the event of the recess 8 being of no value in recording the days of a month, a date eliminating slide 9, movably positioned in the backing 3 and disposed between the frame 1 and the sheet 5, is moved to a position obstructing the view of the numerals. The slide 9 is also provided with an integral upwardly extending projection 10, which is adapted to aline with the horizontal column *c* of the sheet 5, said projection being movable so that the variance in the number of days found in the latter part of the month will be accurately presented, this being accomplished by moving the slide 9 so that the projection 10 thereof will obstruct from view 45 certain higher numerals of the columns *c*, so that months containing but thirty days will not be recorded as containing thirty one. The sheet 5 and the slide 9 are provided with buttons 11, so that the same may 50 be manually moved to their proper respective positions, in order that the numerals found in the sheet 5 will correctly portray the proper dates of the days occurring in a specified month.

55 From the foregoing it will be manifest that devices are provided for correctly and conveniently alining the dates of months in proper relation to the days of the weeks upon which they occur, and, also, additional 60 means, such as the slide 9, for obstructing the view of certain of the higher numerals or dates found on the sheet 5 when the same are of a superfluous nature.

After having described the date disclosing

mechanism, the month and year indicating 65 means may be described as consisting of a plurality of rotatable disks 12 and 13. The disk 12 is provided with the names of the months of a year printed or otherwise denoted thereon, the latter being arranged 70 in the radial manner disclosed in Fig. 2 of the drawings. An operating handle 14 is secured to the disk 12 and is located on the front of the calendar, whereby upon rotating said handle, the disk 12 will be revolved to 75 cause any one of the months indicated thereon to register with a slot 15 formed in said frame 1, in order that the names of a month will be clearly visible from the front view 80 of the calendar.

While the present embodiment of the calendar is formed to provide the year indicating mechanism 13, it is to be understood that this mechanism can very readily be omitted, inasmuch as such mechanism is 85 very seldom observed, as those having use for a calendar are generally cognizant with the date of a year in which they are living. However, to provide for such a contingency, and to finish the completeness of the calendar, the year mechanism 13 is utilized in the preferred form of the invention, and consists of the disk 13, similar to the disk 12, having year indicating indicia 16 thereon which, when the disk 13 is rotated by the 90 handle 17 thereof, will cause one of the years indicated thereon, to register with the openings 18, where it may be seen from the front of the calendar.

After having described the invention it 100 is thought that the construction and operation thereof will be clearly apparent to those versed in the art and, therefore, a more extended explantion has been accordingly omitted. The calendar is constructed of few 105 and simple parts which can be readily assembled in operative relation, and requires attention but once a month to effect its adjustments. By its relatively flat construction it may be readily suspended from a vertical support in the manner of an ordinary 110 calendar, or may be formed as a part of a desk blotter or surface.

As many changes could be made in the above construction and many apparently 115 widely different embodiments of the invention could be made without departing from the scope thereof, it is intended that all matter contained in the above description or shown in the accompanying drawing shall 120 be interpreted as illustrative and not in a limiting sense.

Having described the invention what is claimed as new and patentable is:—

A perpetual calendar comprising a frame 125 having a chamber therein and an opening in its front face, said opening having an extension at its lower edge adjacent one side

thereof and a second extension in the opposite side, the bottom of the second extension being on a line with the bottom of the opening, a date carrying sheet slidably mounted 5 in said chamber and visible through the opening, a button carried by said date sheet, a slide movably mounted in said chamber at the lower part thereof and having its upper edge stepped, and a button on said 10 slide engaging the lower edge of the open-

ing and adapted to enter the second extension for removing the end of said slide from the first extension.

In testimony whereof I affix my signature in presence of two witnesses.

ALEXANDER LECKEY.
